W. A. RINGLER

LOOSE LEAF BINDER FOR MEMORANDUM BOOKS AND SIMILAR DEVICES

Filed July 31, 1924

Patented Oct. 4, 1927.

1,644,034

UNITED STATES PATENT OFFICE.

WILLIAM A. RINGLER, OF PHILADELPHIA, PENNSYLVANIA.

LOOSE-LEAF BINDER FOR MEMORANDUM BOOKS AND SIMILAR DEVICES.

Application filed July 31, 1924. Serial No. 729,215.

The object of my present invention is to employ a novel construction and arrangement of loose leaf binder which can be economically manufactured and which will be durable and reliable in service.

With the above and other objects in view which will hereinafter more clearly appear, my invention comprehends a novel construction and arrangement of a loose leaf binder.

10 It further comprehends a novel construction of loose leaf binder which consists of but two parts, the first part comprising a holder made of a single piece of material having its ends adapted to be clamped to the cover, provided with resilient flanges, and having a portion deflected to form a stop, the other part consisting of a wire, the free ends of which are deflected and extend in opposite direction so that it is adapted to be threaded

20 through and engage with an aperture of the filler, with the free ends extending into the apertures of the filler with which they register.

It further comprehends a novel construction of one piece holder having resilient side flanges provided with an inturned edge to form a guide or shoulder and with a deflected portion forming a stop for the means which secures the sheets of the filler in assembled position.

30 It further comprehends a novel filler having elongated apertures, the sheets of which are secured together by means of two longitudinally extending members having their free ends deflected and adapted to enter the apertures of the filler with which they register.

Other novel features of construction and advantage will hereinafter more clearly appear in the detailed description and the appended claims.

40 For the purpose of illustrating the invention, I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and that the invention

50 is not limited to the precise arrangement and organization of these instrumentalities as herein set forth.

Figure 1 is a plan view of a memorandum book in conjunction with which a loose leaf binder embodying my invention is employed.

Figure 2 is a section on line 2—2 of Figure 1.

Figure 3 is a section on line 3—3 of Figure 2.

Figure 4 is a sectional view of the filler seen in Figure 2.

Figure 5 is a top plan view of holder and a portion of the cover.

Figure 6 is a sectional view of a filler, 65 with filler assembling means embodying my invention.

Figure 7 is a side elevation of a portion of a sheet of the filler seen in Figure 6.

Similar numerals of reference indicate corresponding parts.

Referring to the drawings:

1 designates the body portion or holder of a loose leaf binder embodying my invention.

This holder is made of a single sheet of material and preferably of spring metal, the marginal portions of which are outwardly deflected to form the resilient flanges 2 and 3 respectively. Each flange has its edge 75 inwardly deflected, as at 4, to form a guide or shoulder.

The free ends of the holder are of reduced width, as at 5, and are bent over the cover 6 and pressed against it and the free ends terminate in the terminals 7 which pass through the apertures 8 in the body portion of the holder so that the holder is rigidly secured to the cover. The flanges 2 and 3 at one end are laterally deflected, 80 as at 9, to form a stop.

10 designates the filler which is provided along its inner marginal edge with the spaced apertures 11. The sheets of the filler are secured together by securing means 12 which consists of a wire having the free ends 95 bent in opposite directions as at 13 and 14. The wire 12 is bent to provide the longitudinally extending portions 15 and 16 which are connected by the portions 17 at 100 right angles thereto. The wire is passed through one of the apertures 11 so that the portions 17 extend therethrough and the free ends 13 and 14 are inserted into the apertures with which they, respectively, 105 register.

Instead of employing a single wire I may employ two wires 18 and 19 respectively, see Figure 6, the free ends of the wire 18 being deflected in one direction as shown at 20 and 21 and the free ends of the wire 19 being deflected as shown at 22 and 23. Where

two wires are employed, it is preferable to employ apertures 24 in the filler 10, which the free ends of the wire substantially fill.

In the operation, assuming that the holder 5 has been secured to the cover and the single wire is employed to secure the sheets of the filler in assembled position, the filler is inserted between the flanges of the holder so that the wire will lie beneath the shoulders 10. The filler is then slid into position until it engages the stop member formed by the inturned flanges 9. In case the two wires are employed to secure the filler in assembled position, the two wires are assembled 15 as shown with respect to the filler, and the filler is then inserted so that the wires 18 and 19 pass beneath the shoulders 4.

The purpose of having the side flanges 2 and 3 resilient is to enable the holder to 20 accommodate fillers of different widths. As the holder is preferably made of spring metal, the flanges will normally incline towards each other, and when the filler is inserted these resilient flanges will be under 25 tension and firmly grip the filler, so that there is no likelihood of its becoming accidentally disengaged from its holder.

It will be noticed that where a single wire 30 is employed to secure the sheets of the filler in assembled position the hole through which the portion 17 of the wire passes is elongated and as illustrated, it is of an oval contour. This provides for the use of fillers of different thicknesses. The wire itself is 35 preferably of comparatively soft metal so that it can be bent at the points where the portion 17 connects with the longitudinal stretches of the wire so that the filler will be properly retained in assembled position 40 and the free ends can be brought into registry with apertures in the filler.

In case two wires are employed to retain the sheets of the filler in assembled condition, the holes into which the free ends of 45 such wire passes, are preferably slightly larger than such free ends.

It will thus be apparent that irrespective of the thickness of the filler, the free ends of either a single wire or a number of 50 wires can readily be brought into registry with the apertures into which they are intended to extend and the sheets of the filler will be retained in assembled position when the filler is slid into place between the resilient side flanges of the holder.

If a single wire is employed, one stretch is preferably longer than the other so that the free ends will engage different apertures. If two wires are employed they may be of 60 the same or of different lengths, as is apparent, although I preferably use wires of the same lengths.

It will be apparent that my present invention 65 can be very economically manufactured since the holder is formed from a single sheet

of material and if one wire is employed to bind the leaves of the filler together, only two parts are necessary.

The holder is secured to the cover by fastening devices which are integral with the 70 holder.

This invention, although not limited to such use, is specially adapted to be employed in conjunction with fillers, the leaves of which are so thin that they cannot be retained in position by the ordinary type of ring binders where the rings go through 75 apertures in the leaves.

It will now be apparent that I have devised a new and useful loose leaf binder for 80 memorandum books and similar devices which embodies the features of advantage enumerated as desirable in the statement of the invention and the above description, and while I have, in the present instance, shown and described a preferred embodiment thereof 85 which will give in practice satisfactory and reliable results, it is to be understood that this embodiment is susceptible of modification in various particulars without departing from the spirit or scope of the invention or sacrificing any of its advantages.

Having thus described my invention, what I claim as new and desire to secure by Letters Patent, is:

1. A loose leaf binder, comprising a holder adapted to be secured to a cover and having resilient side flanges, each of which has its free marginal edge bent inwardly to form a shoulder, a filler insertable between said flanges, and fastening means for said filler adapted to lie beneath said shoulders when said filler is inserted between said flanges and provided with free ends deflected to pass into the filler and retained therein by said side flanges.

2. A loose leaf binder, comprising a holder formed from a single sheet of material and adapted to be secured to a cover, said holder having resilient side flanges the free marginal edges of which are bent inwardly to form shoulders, and a stop at one end, a filler having laterally spaced apertures and insertable between said flanges to engage said stop, and fastening means comprising a wire having free ends to enter different apertures with which they register, said means co-operating with said shoulder to retain said filler in place in the holder.

3. A loose leaf binder, comprising a holder adapted to be secured to a cover and having resilient side flanges the free marginal edges of which are bent inwardly to form shoulders, a filler having apertures and insertable between said flanges, and a wire passing through one of said apertures and having longitudinally extending stretches, the free ends of which extend in opposite directions into different filler apertures with which they register.

4. A loose leaf binder, comprising a holder adapted to be secured to a cover and having resilient side flanges with shoulders, a filler having apertures one of which is elongated and insertable between said flanges, and a wire passing through said elongated aperture and having longitudinally extending stretches extending laterally in the same direction on opposite sides of the filler, the free ends of which extend into different filler apertures with which they register.

5. A loose leaf binder, comprising a holder

adapted to be secured to a cover and having resilient side flanges with shoulders, a filler insertable between said flanges, said filler having apertures near one of its marginal edges and two wires with deflected ends arranged on opposite sides of the filler and disposed laterally thereof with their ends extending into the different apertures with which they register, said wires being adapted to engage said shoulder when said filler is inserted between said flanges.
